Int. Cl. D14—03

U.S. Cl. D56—4

The single figure is a left side, top and front perspective view of a radio cabinet or similar article showing my new design and employing two loudspeaker grille cloths each shaped like a four-side truncated pyramid and continuous within the boundaries shown. The dominant features of my new design are shown in solid lines in the drawing.

I claim:

The ornamental design for a radio cabinet or similar article, as shown and described.
